UNITED STATES PATENT OFFICE.

JOHN GERARD, OF NEW BRITAIN, CONNECTICUT.

DOOR CHECK AND CLOSER.

1,076,205.

Specification of Letters Patent.

Patented Oct. 21, 1913.

Application filed October 26, 1912. Serial No. 727,632.

To all whom it may concern:

Be it known that I, JOHN GERARD, a citizen of the United States, residing at New Britain, Hartford county, State of Connecticut, have invented certain new and useful Improvements in Door Checks and Closers, of which the following is a full, clear, and exact description.

This invention relates to the art of combined door checks and closers and more particularly to a device of this character applied as a "floor hinge" for a door. In such devices, the body of the combined check and closer is loosely seated in or on the floor at the inner end of the door and is provided with a pivot to which the door is connected.

My present invention is designed to provide a structure of this character wherein the closer and check elements are very compactly arranged; wherein the closer element is accurately guided within the case; wherein the closing power is greatest when the door is closed and decreases progressively with the opening of the door; wherein the parts of the closer and check are easily accessible; and wherein the casing for said parts is solid except for removable ends which provide the openings for inserting and withdrawing the operating parts and which minimize the area for possible leakage. These and various other features of improvement are described in detail in the following specification and are shown in the accompanying drawings forming part thereof and illustrating a preferable embodiment of the invention.

In these drawings, Figure 1 is a top plan view of the assembled device, a portion of the finish plate being broken away. Fig. 2 is a view in front elevation of the parts shown in Fig. 1. Fig. 3 is a horizontal section through the casing and its contained parts. Fig. 4 is a vertical section through said casing and parts. Fig. 5 is a vertical section through the casing, the ends thereof being removed, together with the interior mechanism. Fig. 6 is a transverse vertical section on the line 6—6 of Fig. 4. Fig. 7 is a top plan view of one of the levers of the closer mechanism. Fig. 8 is a front elevation of the lever shown in Fig. 7. Fig. 9 is a view in elevation of the closer cam, pivot stud and check crank assembled. Fig. 10 is a top plan view of the parts shown in

Fig. 9. Fig. 11 is an end view of a cross-head and cylindrical spring cage. Fig. 12 is a front elevation of the parts shown in Fig. 11. Fig. 13 is a fragmentary top plan view of the cylindrical end closure of the 60 casing.

Referring to the parts by numerals, 1 indicates generically the check and closer casing which is of substantially tubular form and which is integral except for removable ends 2 and 3 screwing into the body of the casing, the end 3 being provided with a cylinder 4 extending therefrom to form the cylinder of a liquid checking mechanism to be hereinafter described. The casing at 70 its base is formed with a seat 5 for the lower end of the pivot stud and with enlargements or swells 6 at opposite sides.

In the top of the casing I provide a threaded bore 7 for the pivot stud and its 75 bushing, and a second and adjacent threaded bore 8 for the pivot stud of the closer levers. The pivot stud which is inserted through the threaded bore 7 has upper and lower rounded ends 9 and an intermediate 80 squared portion 10. The lower end of this pivot stud is adapted to be fitted within the seat 5 of the casing, and the upper rounded end is positioned within the threaded bore 7 of the casing. The extreme upper end of this pivot stud is flattened at opposite sides as at 11, and a door plate 12 fits over the flattened upper end of the stud and is suitably secured to the under side of the door so that the pivot stud will turn with the swinging 90

of the door. Fitting over the upper end of the squared shank 11 is a sleeve 13 having an offset bearing arm 14, while a second sleeve 15 fits over the lower end of the squared portion 11 and is provided with a 95 second and alined offset bearing arm 16. These two sleeves are connected by means of a pin 18 secured to the two offset arms 14 and 16 respectively. An anti-friction roller 17 is journaled on this pin and is positioned between the two bearing arms hereinbefore mentioned. The second and lower sleeve 15 has extending therefrom at a point opposite the bearing arm 16, a crank arm 19 suitably apertured for the purpose hereinafter described. The pivot stud with its sleeves, arms and anti-friction roller is supported within the casing by means of a bearing washer 20 seated over the lower end of the pivot stud and resting 110

on the bottom of the casing adjacent the seat 5, a ball race 21 being seated over this bearing washer, and a second bearing washer 22 being seated over the ball race and supporting the under face of the sleeve 15.

As before stated, the pivot stud is inserted into the interior of the casing through the threaded bore 7 thereof. The diameter of the stud itself is less than the diameter of this bore, and I provide threaded bushings 23 which screw into the threaded bore 7 of the casing, and preferably also a packing ring 24 so that leakage at this point is prevented.

15 A piston 25 is seated in the cylinder 4 and is provided with a piston rod 26 connected thereto by the usual wrist-pin 27. The inner end of the piston rod is provided with a pin 28 which is removably seated in the aperture formed in the crank arm 19. The body of the piston 25 is provided with a ball check valve 29 of usual construction, this valve opening on the inward stroke of the piston and closing on the outward stroke.

20 The cylinder 4 adjacent its outer end is provided with an outlet passage 30^a and with a groove in its threaded portion forming a by-pass 30 communicating with the outlet 30^a and with the interior of the casing. This 25 by-pass affords a restricted outlet opening for the oil or other fluid with which the casing is filled, and the size of this restricted aperture may be increased or diminished by means of a regulating screw 31 which extends through the end of the casing and into the outlet 30^a so that it may be moved in or out to partially cover, and thereby vary the size of the opening into the by-pass 30. The casing where the regulating screw 31 extends therein is provided with suitable packing glands similar to those used in connection with the pivot stud. The specific forms of these packing glands or bushings as well as the by-pass and regulating screw are old 40 and may be modified at pleasure.

The cylinder 4, piston 25 with its rod 26 and regulating valve, comprise the liquid checking element of the device. Associated with this liquid check is an independent 50 closer mechanism as follows: Mounted within the casing at the forward end thereof is a cylindrical spring cage 32 which is concentric with and partially incloses the cylinder 4. This cylindrical cage at its inner end 55 is provided with a cross-head plate 33 detachably secured thereto and provided with guiding wings 34 at opposite sides, which wings extend out into the enlargements 6 of the casing. A coiled spring 35 is mounted within 60 this cylindrical cage 32, its forward end abutting against the forward end of the casing and its rear end against the inner rear end of the cylindrical cage, and the spring itself encircling the cylinder 4. By making 65 the cylindrical cage concentric with the cyl-

inder 4, I am enabled to provide a special space whereby a relatively long spring may be employed and yet afford a very compact structure.

Coöperating with the spring cage and 70 with the anti-friction roller carried by the pivot stud, are complementary bell-crank levers 36 having their pivotal ends apertured. The forward arms 38 of each of these levers is bifurcated and provided with an anti-friction roller 39 journaled with the bifurcation, while the rear arms 40 of these levers are enlarged transversely at their ends to afford a contact surface of an area corresponding substantially with the anti-friction roller 17. The inner faces of each of the levers is formed on a curve as at 41 for the purpose hereinafter described. The pivotal ends 37 of each of the levers 36 are shouldered down so that they are of less thickness than the body of the lever. This is done in order that these ends of each lever may be overlapped at the pivotal point and bring the arms of the levers in the same plane. It will be understood, of course, that 80 the two levers 36 are similar generally, but that their pivotal ends 37 are oppositely shouldered so that they may overlap as described, and that the enlargements at the ends of their forward arms 40 are oppositely 85 formed, in order that these levers may be "complementary" to each other and may co-operate in the manner described. These levers are pivotally interconnected at their ends 37 by means of a threaded pivot pin 42 90 entering the interior of the casing 1 through the threaded bore 8 therein, and having a tight threaded engagement with said bore. The lower end of the pivot pin 42 is without threads and enters through the aligned apertures in the overlapping pivotal ends of the levers 36 so that these levers may journal thereon. In this connection it will be noted that the piston rod 26 extends beneath the lower of these two complementary levers and 100 retains both levers on their pivot pin and prevents them from dropping therefrom. The anti-friction rollers 39 at the ends of the forward arms 38 of these levers rest against the wings 34 of the spring cage 115 cross-head 33 while the rear ends of these levers, when the door is closed, (see Fig. 3) rest against opposite sides of the anti-friction roller 17 carried by the pivot stud, this roller 17 acting as a cam to move the levers 120 on their pivots.

The cylindrical spring cage 32, with its cross-head, is spaced from the interior walls of the casing and guided longitudinally therein by a plurality of ribs 44 extending inwardly from the walls of the casing 1, while the case is prevented from rotating by the wings 34 of the cross-head guiding in the enlargements 6 of the casing, and its forward movement limited by the casing at the 130

forward end of said enlargements. The top of the casing 1, when it is seated in the floor, is covered by a finish plate 45 secured to the casing by any suitable means, as by the screws shown in the drawing.

From the foregoing it will be evident that the operation of the door closer and check is as follows: The casing 1 being filled with oil or other liquid, and assuming that the door is closed with the parts in the position shown in Figs. 3 and 4, the opening of the door in either direction from central closed position will, through door plate 12, turn the pivot stud with its attached parts. This movement of the pivot stud will bring the cam roller 17 against one or the other enlarged ends 40 of the levers 36 and will swing said levers on their pivot pin 42 and bring an anti-friction roller 39 against one of the wings 34 of the cross-head, moving said cross-head and its attached spring cage forwardly to compress the coiled spring 35. As the cam roller 17 turns during this movement, it will first engage the enlarged end of the active arm 40 and will then ride over the curved inner face 41 of the active lever member 36. The leverage secured by this cam roller against a lever member 36 is greatest when the parts are in door closed position, and the force of the closer spring 35 is exerting its most powerful leverage against the cam roller 17 of the pivot stud when the door is in this position.

When the door is released, the compressed coiled spring 35 will force its cylindrical cage 32 and the wings 34 carried thereby against the active anti-friction roller 39, forcing its forward arm 40 against the cam roller 17, and through its pivot stud, swinging the door to closed position. The leverage secured through the lever member 36 against this cam roller 17 upon the return movement is greatest when the door reaches closed position so that a maximum resistance to draft is afforded by the closer spring when the door is in closed position.

When the door is opened and the coiled spring 35 compressed as described, the crank arm 19 carried by the collar 15 of the pivot stud, will move the piston rod 26 and piston 25 rearwardly or toward the pivot stud, the ball valve 29 opening during this movement and permitting the liquid within the casing to flow freely through the piston. On the return movement of the door, the piston rod 26 and piston 25 are moved forwardly and the ball check valve 29 closes. The liquid remaining in front of the piston is then forced thereby through the outlet 30^a and by-pass 30 to the exterior of the cylinder 4 in the manner as is usual in door checks of this character.

It will be noted that the operation of one closer lever 36 is independent of the other and that by reason of the guiding means

provided for the spring cage and cross-head, the pressure, although applied at one side, compresses the closer spring substantially uniformly. It will be also noted that I have pivoted the lever members 36 on an axial line through the center of the casing so that a greater leverage is secured than if these levers were pivoted at a point outside of the center line. This construction gives a maximum forward movement to the forward ends of the levers 36 engaging the cross-head with a minimum movement radial thereto and insures greater compactness in construction. This arrangement, as has been heretofore pointed out, also enables the closer spring 35 to exert its maximum closing effect when the door is closed, and as the door is opened in either direction away from the center, the spring resistance becomes progressively less by reason of the decreasing leverage.

By providing, in a device of this character, a casing in which the only openings for inserting the operating parts are at the front and rear ends, the top, sides and bottom being solid, I am enabled to largely reduce the area of possible leakage, and in addition have afforded means whereby access to the interior of the casing may be conveniently had. It will be noted in this connection that the cylinder of the liquid checking device is carried by one of the removable end caps.

While I have described and illustrated a specific embodiment of my device, I desire it is understood that many structural changes are possible within the spirit of the invention and the scope of the appended claims.

What I claim, therefore, and desire to secure by Letters Patent is:

1. In a device of the character described, in combination, a casing, a pivot stud rotatably mounted therein and adapted for operative connection with a door to rotate with the opening and closing thereof, a checking mechanism embodying a cylinder mounted within said casing and a piston within said cylinder operatively connected with said pivot stud to reciprocate with the movement thereof, and a spring closer mechanism independent of said checking mechanism and embodying a spring mounted within said casing substantially concentric to and inclosing said checking cylinder, a sliding head substantially concentric to said cylinder and engaging said spring, and a lever member within said casing pivoted on the line of axis of said cylinder and spring and engaging said head eccentrically of said axis and arranged to be operated by the rotation of said pivot stud to move said head to tension said spring, and operated by the tensioned spring to return said lever member and stud to normal position.

2. In a device of the character described,

in combination, a casing, a pivot stud rotatably mounted therein and adapted for operative connection with a door to rotate with the opening and closing thereof, a checking mechanism embodying a cylinder mounted within said casing and a piston within said cylinder operatively connected with said pivot stud to reciprocate with the movement thereof, and a spring closer mechanism independent of said checking mechanism and embodying a spring mounted within said casing substantially concentric to and inclosing said checking cylinder, a sliding head substantially concentric to said cylinder and engaging said spring, complementary lever members mounted within said casing and operated by the rotation of said pivot stud to move said sliding head to tension said spring, and operated by the tensioned spring to return said pivot stud and door to normal position, said lever members being independently operable in opposite directions of rotation of said pivot stud.

3. In a device of the character described, in combination, a casing, a pivot stud rotatably mounted therein and adapted for operative connection with a door to rotate with the opening and closing thereof, a checking cylinder within said casing having a piston therein operatively connected with said pivot stud to reciprocate with the rotation thereof, a closer spring within said casing inclosing and substantially concentric to said checking cylinder, a cross-head abutment engaged by said spring and concentric to said checking cylinder, and a bell crank lever pivotally mounted within said casing on an axial line through the center of said casing and in operative connection with said pivot stud and cross-head whereby rotation of said pivot stud with the opening of the door operates said lever to move said cross-head to tension its spring, said spring, when tensioned, being adapted to move said lever to return said pivot stud and door to normal position.

4. In a device of the character described, in combination, a casing, a pivot stud rotatably mounted therein and adapted for operative connection with a door to rotate with the opening and closing thereof, a checking cylinder within said casing having a piston therein operatively connected with said pivot stud to reciprocate with the rotation thereof, a closer spring within said casing inclosing and substantially concentric to said checking cylinder, a cross-head abutment engaged by said spring and concentric to said checking cylinder, complementary bell crank levers concentrically pivoted on an axial line through the center of said casing and having their ends in operative connection respectively with said pivot stud and cross-head abutment whereby movement of the door, and consequent rotation of the pivot stud, will actuate one of said bell crank levers independently of the other to move said cross-head abutment to tension its spring, and whereby said spring, when tensioned, is adapted to move said lever to return said pivot stud and door to normal position.

5. In a device of the character described, in combination, a casing, a pivot stud mounted therein and adapted for operative connection with a door to rotate with the opening and closing thereof, a checking cylinder within said casing provided with a piston therein operatively connected with said pivot stud to reciprocate with the rotation thereof, a closer spring within said casing, a sliding cylindrical holder within said casing inclosing and engaged by said spring and provided with an abutment, said holder and spring being concentric to and inclosing said checking cylinder, complementary bell crank levers pivotally mounted within said casing on an axial line through the center of said casing and having their ends in operative connection respectively with said pivot stud and spring holder whereby movement of the door, and consequent rotation of the pivot stud, in either direction will actuate one of said bell crank levers independently of the other to move said spring holder to tension its spring, and whereby said spring, when tensioned, is adapted to move said lever to return said pivot stud and door to normal position.

6. In a device of the character described, in combination, a closed casing, a pivot stud mounted therein and adapted for operative connection with a door to rotate with the opening and closing thereof, a checking cylinder within said casing provided with a piston operatively connected with said pivot stud to reciprocate with the rotation thereof, a closer spring within said casing, a cross-head within said casing provided with a cylinder housing said spring, said cross-head and cylinder being movable longitudinally of said casing, guiding means within said casing engaging and guiding said cross-head and cylinder during said movement, and operative connections between said pivot stud and cross-head whereby said cross-head is moved by the rotation of said pivot stud to tension said closer spring, and whereby said spring, when tensioned, is adapted to actuate said connections to return said pivot stud to initial position.

7. In a device of the character described, a casing comprising a hollow tubular body portion having an open end, a removable closure for said open end having a liquid checking cylinder rigid therewith and extending from said end closure into the interior of the tubular body portion, a reciprocating piston within said body portion co-

operating with said cylinder, said cylinder having a liquid by-pass formed therein adjacent is outer end.

8. In a device of the character described, 5 a casing comprising a hollow tubular body portion having an open threaded end, a removable closure for said open end having a liquid checking cylinder rigid therewith, and of less diameter and extending from 10 said end closure into the interior of the tubular body portion, said cylinder being exteriorly threaded to engage the threaded open end of said tubular body portion and having a liquid by-pass formed therein adjacent its outer end, and a reciprocating 15 piston within said body portion coöperating with said cylinder.

9. In a device of the character described, 20 in combination, a casing, a pivot stud rotatably mounted therein and adapted for operative connection with a door to rotate with the opening and closing thereof, a checking cylinder within said casing having

a piston therein operatively connected with said pivot to reciprocate with the rotation 25 thereof, a closer spring within said casing inclosing and substantially concentric to said checking cylinder, a reciprocating abutment head substantially concentric to said closer cylinder and 30 engaged by said spring, said head having a portion guided longitudinally by said casing, an actuating lever pivoted within said casing in line with the axis of said spring and cylinder and in operative connection with said pivot stud, said lever engaging said abutment head eccentrically of 35 said axis and being operated by rotation of said pivot to move said abutment head to tension said spring and being operated by 40 said tensioned spring to return said pivot stud to initial position.

JOHN GÉRARD.
